US00D598801S

(12) **United States Design Patent**
Behling

(10) **Patent No.:** **US D598,801 S**
(45) **Date of Patent:** **** Aug. 25, 2009**

(54) **WATCH DIAL**

(75) Inventor: **Christoph Behling**, London (GB)

(73) Assignee: **Tag Heuer SA**, La Chaux-de-Fonds (CH)

(**) Term: **14 Years**

(21) Appl. No.: **29/325,272**

(22) Filed: **Sep. 29, 2008**

(30) **Foreign Application Priority Data**

Mar. 31, 2008 (WO) DM/069 999

(51) **LOC (9) Cl.** **10-07**

(52) **U.S. Cl.** **D10/126**

(58) **Field of Classification Search** D10/122-132, D10/30-39; 368/28, 80, 223, 228, 232

See application file for complete search history.
